EX
OR D 12,800

No. 12,800

MARCH 7, 1885

UNITED STATES PATENT OFFICE.

REBECCA McLAUGHLIN, OF PHILADELPHIA, PENNSYLVANIA, ASSIGNOR TO
E. H. GODSHALK, OF SAME PLACE.

DESIGN FOR FRINGE.

SPECIFICATION forming part of Design No. 12,800, dated March 7, 1882.

Application filed February 9, 1882. Term of patent 3½ years.

To all whom it may concern:

Be it known that I, REBECCA McLAUGHLIN, a citizen of the United States, residing in the city and county of Philadelphia, State of Pennsylvania, have invented and produced a new and original Design for Fringe, of which the following is a specification, reference being had to the accompanying photographic illustration, forming part thereof, which is a face view of a piece of fringe embodying my design.

The design consists of a fringe having a head, A, to which is attached a series of pendants, B, a number of which are formed into a bunch and gathered intermediate of their ends, as at a, and united at the place of gathering, at which place a rosette, C, is secured. The bottom of the pendants are provided with balls or bulbs D.

The pendants, which may be composed of chenille threads, may be of any desired color, either uniform in tint or shaded.

The design is of a beautiful and attractive nature.

I claim—

1. The design for fringe, consisting of a head having a series of pendants which are formed in bunches gathered intermediate of their ends, substantially as set forth. 25

2. The design for fringe, having pendants which are formed in bunches gathered intermediate of their ends, and rosettes at the place of gathering of the pendants, substantially as set forth. 30

3. The design for fringe, consisting of a head, pendants which are bunched and gathered, rosettes, and balls or bulbs, substantially as set forth. 35

REBECCA McLAUGHLIN.
